DESIGN FOR A TRAY

Louis M. Dennis, Ithaca, N. Y.

Application May 15, 1936, Serial No. 62,651

Term of patent 7 years

To all whom it may concern:

Be it known that I, Louis M. Dennis, a citizen of the United States, residing at Ithaca, in the county of Tompkins and State of New York, have invented a new, original, and ornamental Design for a tray, of which the following is a specification, reference being had to the accompanying drawing, forming part thereof.

The figure is a perspective view of a tray, showing my new design.

The distinguishing features of my design reside in the smoothly tapering character of the side walls of the tray and cross supports, the proportioning of the parts and the blending of the tapering cross supports into the tapering sides below the level of the top of the tray.

I claim:

The ornamental design for a tray, as shown and described.

LOUIS M. DENNIS.
